UNITED STATES PATENT OFFICE.

WILLIAM F. MAHER, OF NEW YORK, N. Y.

DESIGN FOR A CLOCK-FACE.

58,444.

Specification for Design.

Patented July 19, 1921.

Application filed June 5, 1920. Serial No. 386,823. Term of patent 3½ years.

To all whom it may concern:

Be it known that I, WILLIAM F. MAHER, a citizen of the United States, and resident of New York, in the county of Kings and State of New York, have invented a new and original Design for a Clock-Face, of which the following is a specification, reference being had to the accompanying drawing, forming part thereof.

The figure is a plan view of the face of clock showing my new design.

I claim:

The ornamental design for clock face, as shown.

Signed at New York, in the county of New York, and State of New York, this 14th day of May, A. D. 1920.

WILLIAM F. MAHER.
